TELEPHONE SYSTEM.

940,693.

Specification of Letters Patent. Patented Nov. 23, 1909.

Application filed December 28, 1906. Serial No. 349,854.

To all whom it may concern:

Be it known that I, DAVID S. HULFISH, a citizen of the United States of America, residing at Chicago, county of Cook, and State 5 of Illinois, have invented a new and useful Improvement in Telephone Systems, of which the following is a specification.

My invention pertains to semi-automatic telephone exchange systems; it lies in the 10 class of systems wherein the work of manual operators is facilitated by automatic apparatus placed between the calling subscriber and the operator; its object is to promote team work between the operators at a manual 15 multiple board.

In the system of my invention, I provide multiple answering jacks, and thus provide a means whereby any line may institute an 20 originating call before any one of a plurality of operators; in connection with the answering jacks, I provide call-controlling or Y-devices for announcing the call to the operator, the object of the call-controlling devices being four-fold: first, to give but one 25 call to an operator, and to withhold other calls until the first call assigned has been answered; second, to assign a calling line to a definitely selected operator, and to withhold that line from calling signals before other 30 operators until the operator first selected has signified an unwillingness or inability to answer the call; third, to assign calling lines consecutively to operators in the order of the connection of the lines in each call-controlling device, thus protecting any definite 35 line from discrimination through negligence of the operator; and, fourth, to distribute the calls of a multiplied group of lines impartially to all of the operators assigned to 40 that group of lines, in contradistinction to systems in which originating calls are assigned to a given operator standing first in precedence, and are assigned to the other operators only when there is an overplus of 45 calls after the first operator is working at full capacity, and in which the work of the lines is thereby unequally divided among the several operators serving the group of lines.

One figure accompanies this specification in which is set forth an arrangement of multiplying lines with reference to calling jacks and answering jacks which will conform to 50 my system of operating and in which the electrical requirements of the call-controlling

device are set forth, together with a suggestion of the mechanical details required; the entire figure is drawn with reference to the present circuits of a well known type of relay multiple switchboard and the cord circuit commonly associated therewith.

In the figure, S is a substation telephone equipment associated with the line 1, which in the central office passes through the distributing frame D, becoming conductors 11 65 in the cabling to multiple calling jacks and becoming conductors 12 in the cabling to the multiplied answering jacks. In the group of lines here considered, the lines are multiplied with calling jacks at A, B and C, 70 which may be assumed to be the multiplying at three consecutive switchboard sections, each section accommodating three switchboard operators; the group of lines is multiplied with answering jacks at A' and C', 75 opposite the calling jack multiple of the lines, thus indicating that in this instance the answering jacks are multiplied before every sixth operator.

A cord pair of a well known type is shown 80 at P. In a switchboard using the type of cord pair shown at P, it is customary to equip each line with a line or calling relay and with a cut-off relay, as well as with a line or calling lamp; these items are not 85 required in the system here illustrated, but for the proper operation of the cord pair P it is necessary to install the resistance R between the test wire of the line and earth. Each group of lines is associated at each 90 group of answering jacks with a call-controlling device which as a whole may be designated Y in the figure. The call-controlling device Y consists of a permutation switch of any desired mechanical type, 95 which tests the lines of the group consecutively by connecting a set of bus wires, 4, 5, 6, with the three conductors of the line in switchboard, stopping in registry with a calling line not previously assigned to an 100 operator, and operating then to assign that calling line to the operator with whom the device Y is associated. One device Y is associated with each operator's position.

Mechanically as shown, the device Y consists of an arm 7 upon a shaft 8, the shaft 8 being rotated continuously by the motor M and its associated worm and gear 9. The arm 7 carries three brushes, 13, 14, 15, bearing continuously upon the three collector 110

rings 18, 17, 16, respectively, and connecting those collector rings to insulated waiting contacts located adjacent thereto. The shaft 8 carries also the pointer 19, traveling over 5 the dial 20; the symbols of the dial correspond to the symbols identifying the answering jacks, and the adjustment of the pointer 19 upon the shaft 8 is such that when the arm 7 stops with its brushes or 10 wipers in contact with the conductors of a calling line, the pointer 19 will indicate upon the dial the identifying symbol of the answering jack associated with that calling line; thus, when the pointer stops, the operator may answer the call by plugging into 15 the answering jack identified by the position of the pointer. Additional parts of the call-controlling device Y are the testing relay 21, the cut-off relay 22, the pilot lamp 23, the emergency switch 24, the master switch 25, the off-normal switch 26, the off-normal cam 27 attached to the shaft 8, the clutch 28 whereby by the energization of the testing relay 21 the motor M may be disconnected from the shaft 8 and the motion of 20 the wipers stopped.

The operation of the system as a whole is as follows: Assume a call upon the line 2, the two conductors of that line will be 30 bridged together at the substation through the talking bridge; when the arm 7 in its travel brings its brushes into connection with the waiting contacts of the line 2, current will flow from battery 29 through elements 25, 24, 30, 31, 5, 17, 14, 33, line 2, substation bridge thereof, line 2 returning, 32, 35 13, 18, 4, 35 and earth, energizing relay 21 by the current through conductor 30 constituting a winding thereof, and by the movement of that relay's armatures accomplishing the following results: First, the clutch 40 28 is operated to disconnect the motor M from the shaft 8, thus stopping the wipers 13, 14, 15; in connection with the calling line and stopping the pointer 19 at "2" upon the dial 20; second, by the right-hand armature of the relay 21 the full potential of the battery 29 is connected directly to the armature 31 of the cut-off relay, and thus to the 45 line conductor of the calling line now being served thus raising the potential of that conductor to the full potential of the battery 29 and preventing the circuit through the substation of that line from operating to energize any other test relay (as relay 21 at position C') which may subsequently connect with the conductors of the line; thus the device Y appropriates the calling line and places upon it proper busy-test conditions to guard it from other call-controlling 50 devices which may serve it jointly with the device illustrated in association with the answering jacks at A' in the figure; third, the left-hand armature of the relay 21 60 closes its contact, giving path for current

through the alternative winding of its own core, extending the energization of the core, regardless of the short-circuiting of the testing winding primarily energizing the core, and also furnishing current for the 70 illumination of the lamp 23, a lamp as a pilot for the device, which will attract the operator's attention to the indicator. The operator, noting the indication of the pointer 19, will insert an answering plug in 75 the jack 2' of the line 2, and proceed to complete the call in the usual manual manner.

By the insertion of the answering plug, current will flow from the battery 29 through the signal conductor of the cord, 80 sleeve of plug, sleeve of jack 2', conductor 34, wiper 15, collector ring 16, conductor 6, and winding of relay 22 to earth, energizing the release relay 22, and by the operation of the armatures of relay 22 opening the circuits of both windings of relay 21, thus permitting the clutch 28 to reengage and move the wipers from the line just served; the progress of the device Y will continue until another calling line is found, regardless of 90 the duration of time required for the operator to complete the connection for the line just assigned her. The line 2 now is busy, the test for busy being evidenced by the potential upon the conductor 34 and the homologous conductor in other Y devices, as regard the automatic portion of the system, and by the potential upon the test rings of the jacks, for the manual portion of the system. When, on subsequent revolutions, the 100 arm 7 brings its wipers into registry with the contacts of the line 2, the wiper 15, being set angularly in advance of the remaining two wipers, will receive current from the test conductor and will operate the 105 cut-off relay 22, thus preventing electrical connection between the talking conductors of the line 2 and the battery or ground associated with the Y device, and thus preventing clicks upon the line by reason of the 110 passing of the brushes of the Y device. This condition of course is true regardless of the identity of the jack, answering or calling, at which the connection between the plug and the line is made.

The off-normal switch 26 is instrumental in stopping the Y device in the proper position, as, when the master switch 25 is opened to throw the operator's position out of service, the circuit will be continued until the pointer 19 reaches the N or normal position, in which position the off-normal switch will break its contact and stop the motor M, and in which position the wipers will rest upon an idle set of contact points, shown black as 115 120 for insulated points in the figure.

The emergency switch 24 is for the use of the operator when for any reason she is unable to answer a call assigned to her by the call-controlling device; a momentary, 130

opening of this key will cause the brushes to move off of the contacts of the calling line, leaving the line to be picked up by some other call-controlling device serving it.

5 Referring to the second paragraph of this specification, the objects of the call-controlling device are explained as follows: First, it is impossible for the indicator to identify more than one calling line at one time; second, when a calling line is indicated by one call-controlling device, proper potential is placed upon the conductors of that line to prevent action for it by any other call-controlling device, but not to prevent the taking 10 of the line by any calling plug in the calling jacks of the multiple, that being the general practice of the large multiple switchboards of today; third, the lines connected to the call-controlling device are tested 15 consecutively, so that no line may be overlooked throughout a complete revolution of the wipers, but to be neglected through one complete revolution it must be arbitrarily abandoned by the use of the emergency key 24; there is no interdependence in the operation 20 of the several call-controlling devices serving a group of lines other than the busy test upon the lines, so that any calling line of the group here illustrated is as likely to be engaged by the Y device at the position C' as 25 by the Y device at the position A', and by the laws of chance the two positions should divide the calls equally if no other positions are serving the same group of lines; and the 30 total number of positions serving a group should divide equally between themselves the total load of the group of lines served, assuming equal diligence among the operators at those positions. When any one Y 35 device is motionless by reason of the pause between the assignment of a call to an operator and the answering of the call by the operator, any further calls upon that group of lines will be taken care of immediately by 40 the other Y devices of the other operator's positions serving that line. By the laws of chance, therefore, an equal distribution of calls among the total number of operators on duty is secured, and not a distribution depending upon an overplus of calls beyond 45 the ability of any preferred operator or group of operators.

It is seen from the diagram that the operator at A' and the operator at C' constitute 50 a team of two operators answering calls upon the same lines and bearing the load equally between them if the load be reasonably light, but bearing the load together in the proportion of their respective abilities if the 55 load be heavy, for the following reasons: First, if the load be light, each operator may answer a call and complete the connection in readiness to answer the next call before the next call comes in, thus permitting 60 the calls to divide between them solely by the

laws of chance; or, of two simultaneous calls, one may go to each operator. Second, if the load be so heavy that each operator is behind with her work and at least one call always is waiting for the release of a call-controlling Y device, then the operator who disposes of her calls most quickly will release her Y device most quickly and most frequently, each release being followed by the immediate designation of another call, so 70 that at the end of a period of observation it will be found that she has carried the major portion of the total load, by reason of her greater ability. It is further seen that these facts obtain when the consideration is 75 made of a larger number of operators working together on the same group of lines, as is indicated by the continuance of the conductors of the answering jacks to the left of the position C' as if to a position E', and 80 so on.

The figure indicates that the answering jacks are multiplied every sixth operator, indefinitely, presumably until a sufficient number of operators have been placed in 85 service to give proper attention to the calls of the group of lines during the busiest hour. Assuming the number of operators to be n , then when the traffic load is reduced by the proportion of 1-to- n or 2-to- n one or 90 two operators of that group may be taken from the switchboard and their positions made idle by opening the switches 25 of those positions; the calls of the group of lines then will distribute equally among the 100 operators remaining. When the traffic load is sufficiently reduced, but one operator will handle the entire group, all calls terminating before her in her call-controlling device.

When it is considered that the operator at 105 A' unites in team work with the operator at her right and at her left handling multiplied answering jacks upon other groups of lines, and when it is considered that the operator at C' unites in team work with the 110 operator at her right and at her left handling multiplied answering jacks upon other groups of lines, and when it is considered further that the operators at the right and left of A' may be serving groups of lines 115 different from those at the right and left of C', it will be seen that in my system the proper distribution of the call-controlling Y devices at the various operators' positions upon a multiple board may result in such a 120 perfect plan of team work among operators that the entire switchboard is united into a single working unit and each operator may work to the limit of her ability, yet none work beyond her ability.

The Y device may have from 100 to 1000 125 lines connected, depending upon the size of the exchange and other conditions requiring study and solution for each installation of the system.

I do not wish to limit myself to the exact details herein illustrated and described, as I understand that many modifications may be made without departing from the spirit or scope of my invention.

Having thus described my invention, what I claim as new and desire to secure by Letters Patent is:

1. In a telephone system, a plurality of 10 lines, manual means for connecting with said lines at a plurality of operator's positions, call-indicating devices at a plurality of operator's positions and having all of the lines accessible to each of the call-indicating devices, and means for causing the indicator of any one of said call-indicating devices to identify a calling line, substantially as described.

2. In a telephone system, a plurality of 20 lines, means for connecting with said lines at a plurality of operator's positions, call-indicating devices at a plurality of operator's positions and having all of the said lines accessible to each of the said call-indicating devices, and means for identifying a calling line by any of said call-indicating devices not otherwise busy, substantially as described.

3. In a telephone system, a plurality of 30 lines, means for connecting with said lines at a plurality of operator's positions, call-indicating devices at a plurality of operator's positions and having all of the said lines accessible to each of the said call-indicating devices, simultaneously calling lines not in number in excess of the number of said call-indicating devices being simultaneously identified by said call-indicating devices, substantially as described.

4. In a telephone system, a plurality of 40 lines, manually operated jacks and switch plugs for connecting with said lines at a plurality of operator's positions, call-indicating devices at a plurality of operator's positions and each having access to all of said lines and collectively indicating and identifying all simultaneously calling lines when the number of simultaneously calling lines is not in excess of the number of call-indicating devices, substantially as described.

5. In a telephone system, a plurality of 50 lines, manually operated means for connecting with said lines, a plurality of operator's positions, a call-seeking and line-identifying device at each of said operator's positions, said lines being terminated in a plurality of said call-seeking devices and each of said call-seeking devices having moving parts adapted to detect a calling line and to stop 60 in registry with the calling line and to identify the calling line to the operator, substantially as described.

6. In a telephone system, a plurality of 65 lines, manually operated means for connecting with said lines, a plurality of operator's

positions, a call-seeking and line-identifying device at each of said operator's positions, said lines being terminated in a plurality of said call-seeking devices and each of said call-seeking devices having moving parts 70 adapted to stop in registry with a calling line not elsewhere connected with and to identify that line to the operator; and each call-seeking device having means for protecting the line thus registered from 75 being detected and identified by others of the call-seeking devices having access to that line, substantially as described.

7. In a telephone system, a line, a plurality of call-indicating devices having access 80 to said line and each adapted to identify said line when said line is calling, and means in each of said call-indicating devices for rendering the said line neutral to the other of said call-indicating devices when said line is identified by any one of said call-indicating devices, substantially as described.

8. In a telephone system, a plurality of 90 lines; call-indicating devices at a plurality of operator's positions and each of said call-indicating devices having all of the said lines accessible; means for causing the call indicator of any of said devices to identify a calling line; manual switching means for answering the call upon the line thus identified, and means for releasing the call indicator from the answered line, substantially as described.

9. In a telephone system, a plurality of 100 lines; manually operated means for connecting with said lines; a plurality of operator's positions; a call-seeking and line-identifying device on each of said operator's positions, said lines being terminated in a plurality of said call-seeking devices, each call-seeking 110 device being adapted to detect a calling line and to identify that line to the operator at whose position the call-seeking device is located, each call-seeking device having means for protecting the line thus identified from being detected and identified by any other call-seeking device; and means for releasing the call-seeking device and operating to release the device upon the manual answering of the identified line, substantially 115 as described.

10. In a telephone system; a plurality of 120 lines; manually operated means for connecting with said lines; a plurality of operator's positions; a call-seeking and line-identifying device on each of said operator's positions, said lines being terminated in a plurality of said call-seeking devices, each call-seeking 125 device being adapted to detect a calling line and to identify that line to the operator at whose position the call-seeking device is located; and means for releasing the call-seeking device and operating to release the device upon the manual answering of the identified line, substantially as described. 130

11. In a telephone system, a plurality of lines; a plurality of operator's positions; means enabling any operator to answer any of said lines; a call-seeking and line-identifying device associated with each of said operator's positions, said lines being terminated each in a plurality of said call-seeking devices, each call-seeking device being adapted to detect a calling line and to identify that line to the operator with whose position the call-seeking device is associated; and means in each call-seeking device for protecting a line thus identified from being detected and identified by any other call-seeking device; and means for releasing the call-seeking device from the identified line and operating to release the device upon the answering of the identified line, substantially as described.
12. In a telephone system, a plurality of lines; a plurality of operator's positions;

means enabling any operator to answer any of said lines; a call-seeking and line-identifying device associated with each of said operator's positions; said lines being terminated each in a plurality of said call-seeking devices, each call-seeking device being adapted to detect a calling line and to identify that line to the operator with whose position the call-seeking device is associated; and means for releasing the call-seeking device from the identified line and operating to release the device upon the effecting of a switching connection with the identified line, substantially as described.

In testimony whereof I have signed my name to this specification in the presence of two subscribing witnesses.

DAVID S. HULFISH.
